UNITED STATES PATENT OFFICE

93,660

DESIGN FOR A CARTON HOLDER

Kenneth Kealy, Oakland, Calif.

Application December 20, 1933, Serial No. 50,157

Term of patent 3½ years

To all whom it may concern:

Be it known that I, **KENNETH KEALY**, a citizen of the United States, residing at Oakland, in the county of Alameda, State of California, have invented a new, original, and ornamental Design for a Carton Holder, of which the following is a specification, reference being had to the accompanying drawing, forming part thereof and of which

Figure 1 is a top perspective with the front side of the holder in the foreground;

Figure 2 is a top perspective with the rear open side in the foreground; and

Figure 3 is an end view looking in the direction indicated by the arrow 3', Fig. 1.

The dominant feature of the present design resides in inverted stepping of the lower edge of the front or face member, the opposed ends of which being disposed at right angles to and in close association with end members terminating downwards in diamond-shaped ends.

I claim:

The ornamental design for a carton holder, as shown and described.

KENNETH KEALY.
